(21) Appl. No.: **29/153,774**

(57) **CLAIM**

(22) Filed: **Jan. 9, 2002**

The ornamental design for a video game management system with surge protection, as shown and described.

(51) LOC (7) Cl. **21-01**

DESCRIPTION

(52) U.S. Cl. **D21/333; D14/496**

FIG. 1 is a front perspective view showing our new design;
FIG. 2 is a rear perspective view thereof;
FIG. 3 is a front view thereof;
FIG. 4 is a rear view thereof;
FIG. 5 is a side view thereof;
FIG. 6 is a side view thereof;
FIG. 7 is a top view; and,
FIG. 8 is a bottom view.

(58) Field of Search .... D21/333, 324, D21/385, 328; D14/412-416, 400, 401, 432, 496; 273/148 B; 463/1, 29-35, 46, 47, 43; D13/110, 133, 184

The portions of the video game management system with surge protection shown in broken lines are for illustrative purposes only and form no part of the claimed design.
